Primary Examiner — Wan Laymon(74) *Attorney, Agent, or Firm* — Collard & Roe, P.C.**CLAIM**

The ornamental design for a cold therapy treatment device, as shown and described.

DESCRIPTION

FIG. 1 is a front view of the cold therapy treatment device showing my design;

FIG. 2 is a back-side view thereof;

FIG. 3 is a top view thereof;

FIG. 4 is a bottom view thereof;

FIG. 5 is a left side view based upon the orientation of FIG. 1;

FIG. 6 is a right side view thereof;

FIG. 7 is a bottom right side and back perspective view thereof;

FIG. 8 is a top, left side and back perspective view thereof;

FIG. 9 is a bottom, right side and front perspective view thereof; and,

FIG. 10 is a top, right side and front perspective view thereof.

The features shown in broken lines show environmental structure only and form no part of the claimed design.
